G. P. HOPPMANN

SWIMMING APPARATUS

Filed Sept. 28, 1927

BY

INVENTOR
G.P. Hoppmann
J. Ledermann
ATTORNEY

UNITED STATES PATENT OFFICE.

GEORG PAUL HOPPMANN, OF BROOKLYN, NEW YORK.

SWIMMING APPARATUS.

Application filed September 28, 1927. Serial No. 222,421.

The main object of this invention is to provide a swimming apparatus which is used in pairs and is worn on each side of the body above the thighs. The invention consists of 5 a frame which is tightly strapped to the torso and consists of fins which are reciprocated back and forth by a kicking movement of the legs to which the apparatus is connected, through means of thongs.

10 The above and other objects will become apparent in the description below, in which characters of reference refer to like-named parts in the drawing.

Referring briefly to the drawing, Figure 15 1 is an application of the swimming apparatus to the body of a person.

Figure 2 is an enlarged side elevational view of the same.

Figure 3 is a top plan view of Figure 2.

20 Figure 4 is an end elevational view of Figure 2.

Referring in detail to the drawing, the numeral 10 indicates an expanse of textile material, such as canvas or the like, which is 25 formed into a vest and is draped over the shoulders, and covers the upper portion of the body up to the diaphragm. The lower end of this vest is secured by rivets or the like to a bar 11 which forms a portion of the 30 frame on which the swimming device is mounted. An adjacent parallel bar 12 is connected to the bar 11 but is separated from the latter by a channel 13. The lower end of a lever 14 is slipped into the channel 13 35 and a pin 15 which passes thru the bars 11 and 12 pivotally secures this lever in the channel. A pair of semi-rigid fins 16 and 17, having a sleeve 18, are slipped over the free end of this lever, the sleeve receiving said lever, 40 as indicated in Figure 3. These fins normally converge toward each other and are capable of being slightly flexed, being formed of such material which will permit such flexibility, celluloid or the like being desirable. Near 45 the opposite frame the lower end of an arm 19 is pivoted on a pin 20 in the channel 13. This arm is connected to a foot bracelet 21, which is worn on both feet of the swimmer, by a thong 22. The arm 19 operates in unison 50 with the lever 14 and is connected thereto in parallel relation, by a connecting rod 23. The lever 14 is normally urged and retained in angular position facing toward the front

of the frame by a coiled spring 24, which is connected, at its opposite ends, to the lever 55 and frame. Web girdles 25, which are adapted to encircle the body, are secured to the frame bar 11 intermediate its length and is adapted to further aid in assisting the vest in securely positioning the swimming device on 60 the body.

This swimming apparatus is adapted to be used by a swimmer who finds it convenient and comfortable to propel himself in the water by kicking of the feet. The swimmer 65 lies prone upon his back with the device strapped in position by the girdle 25 and the vest 10. By bending and straightening the legs 26 a kicking motion of the legs is brought about. Kicking of the legs causes the thongs 70 22 to be pulled when the legs are fully extended, and pulling upon the thongs causes the arm 19 to be rotated forwardly. This arm consequently pulls the lever 14 forwardly 75 against the tension of the spring 24 and the water being baffled by the converging fins 16 and 17 propels the swimmer forwardly with ease and comfort.

It is to be noted that certain changes in form and construction may be made without departing from the spirit and scope of the 80 invention.

I claim:

1. A swimming apparatus comprising a vest, a girdle, a frame attached to said vest and girdle, depending fins pivoted in said frame, and means for swinging said fins to and fro, an arm pivoted in said frame and a thong adapted to be connected to the foot of a swimmer for moving said fin, a lever, a connecting rod joining said arm and lever, and means for normally retracting said fins. 85

2. A swimming apparatus comprising a vest, a girdle, a frame attached to said vest and girdle, depending fins pivoted in said frame, and means for swinging said fins to and fro, an arm pivoted in said frame and a thong adapted to be connected to the foot of a swimmer for moving said fin, a lever, a connecting rod joining said arm and lever, a spring connected to said frame and lever 95 for urging said lever forwardly, said fins converging toward the direction of travel. 100

In testimony whereof I affix my signature.

GEORG PAUL HOPPMANN.
